VACUUM CLEANER

Frederick Riebel, Jr., and Dewey M. Dow, Toledo, Ohio, assignors to Air-Way Electric Appliance Corporation, Toledo, Ohio, a corporation of Delaware

Application August 2, 1935, Serial No. 34,396

19 Claims. (Cl. 15—13)

This invention relates to vacuum cleaners of the type which agitates an air cushion-suspended carpet by means of a high speed motor driven rotary agitator including flexibly mounted beaters, such as that covered in pending application Serial No. 752,270, filed November 9, 1934, of which the present application constitutes a continuation in part.

The object of this invention is to provide a novel and improved rotary agitator embodying a 10 rotating spindle to which are attached axially extending strips of resilient material projecting beyond the periphery of the hub, the outer regions of said strips being enclosed in and supporting 15 rounded channels of wear resisting material which afford beating contact with a suspended floor covering such channels being unconnected with the spindle except by the resilient strips, whereby said beaters may freely flex circumferentially, upon contact with the floor covering so 20 as to cushion the blow which is struck against the rug, and to reduce to a minimum, the loosening of the pile fibers of the rug.

Another object of the invention is to provide 25 such a beater which is sturdy and durable, which will not break down under sustained service conditions, and which will not appreciably stretch or distend away from the spindle axis under the influence of centrifugal force at varying speeds of 30 rotation.

Another object is to provide means for securely 35 mounting the beater in the spindle. Preferably, this means comprises a metal backing channel, into which the resilient strip is secured, preferably by bonding. Means are provided also for reinforcing said backing channel against collapsing under the pressure of set screws employed for holding it in the spindle.

With these and other objects in view the invention 40 consists in the combination and construction and arrangement of the various parts thereof, whereby the objects contemplated are attained, as more fully set forth in the accompanying specifications, pointed out in the claims, and 45 illustrated in the accompanying drawings, in which:

Fig. 1 is a cross sectional view through one end 50 of a vacuum cleaner floor tool embodying the invention.

Fig. 2 is a plan view of the rotary agitator.

Fig. 3 is a partial cross section thereof.

Fig. 4 is a view similar to Fig. 3, of a modified form of the invention.

Fig. 5 is a view similar to Fig. 3 of a modified 55 form of the invention.

Fig. 6 is a view similar to Fig. 3, of a modified form of the invention.

Fig. 7 is a view similar to Fig. 3, of a modified form of the invention.

Fig. 8 is a side elevation, partly in section, of 5 the beaters of Fig. 3.

Fig. 9 is a side elevation of the beater of Fig. 4.

Fig. 10 is a side elevation, partly in section, of a modified form of the beater.

Fig. 11 is a plan view of a vacuum cleaner embodying the invention. Fig. 12 is a side elevation of the same.

The invention is embodied in a vacuum cleaner comprising a hollow handle 1, a bag 2, a fan 3 secured to the handle 1, an electric motor 4 for 15 driving the fan 3, a valve casing 5 formed integrally with the casing of the fan 3 and communicating with the hollow handle 1 and floor tool tube 6 respectively, and a floor tool including a suction chamber 10 supported on wheels 12. 20

A neck 11 connects the suction chamber through the medium of a swivel joint 7 to the tube 6, and an auxiliary motor 14 drives the rotary agitator spindle by means of a belt 15, to agitate the carpet C either when lifted against the mouth of 25 the suction chamber 10 by the suction therein, or when lying flat against the floor. The latter condition will hold when the handle is lifted to tilt the suction chamber downwardly around the axis of the wheels 12. The direction of rotation is indicated by the arrow 17. 30

Socketed in the spindle 13 are brush elements 18 and beaters 19.

In the form shown in Fig. 3, the beater comprises an elongated strip of soft rubber 20, a 35 backing channel 21 in which one side of the strip 20 is bonded, and a beater channel 22, into which the other side of the rubber strip 20 is bonded. The backing channel 21 is preferably of black iron, to which rubber can be successively bonded, and the beater channel 22 is preferably black iron, exteriorly plated with chromium, nickel, or other equivalent non-corrosive metal. 40

Since plating tends to deteriorate the rubber, 45 in the preferred form of the invention, developed to eliminate such difficulty, the rubber strip is molded with an enlarged head 23, uncovered, and the beater channel 22a of stainless steel is secured thereto by crimping its skirt portions 24 50 into the rubber at the base of the head 23, placing the entire head under compression, and extruding pimples of rubber 25 into openings 26 in the side walls of the channel 22a. This prevents the channel from sliding endwise from 55

the rubber strip and assists in retention against radial detachment.

Radial retention is secured by the preforming of the strip with a reduced neck region 45 forming the enlarged head 23 and thence further diminishing the thickness of the neck region by extruding the rubber under pressure from between the regions 24 of the channel.

An alternative means to prevent longitudinal slippage of the channel 22a is that shown in Fig. 10, wherein ears 43 are formed on the ends of the channel, and engage the ends of the rubber strip 23.

A preferred modification of the securing method of Fig. 4, is shown in Fig. 7 wherein the head 46 is connected to neck 45a by shoulders 46a that are almost perpendicular to the neck axis, in their preformed state, and wherein the edges 24a of the channel 22d are forced into the rubber forming the shoulders 46a, extruding the rubber of the head upwardly to fill a space initially occurring between the head 46 and top of the channel. The beater channel, instead of being made of metal, may be of a hard, tough composition material 22, such as a phenolic condensation product (the one known commercially as "Bakelite", for example) or pyroxylin, or hard rubber, or rubber enamel. In the case of "Bakelite", the channel may be secured by cementing. Pyroxylin may be applied by dipping. The same is true of enamel. Hard rubber may be vulcanized in place.

The form shown in Fig. 5 embodies an under channel 22b of black iron or other metal which can be bonded successfully to the rubber, so bonded, and an outer channel 40 of stainless steel, slid endwise over the under channel 22b, and positioned by the engagement of its edges 40 under flanges 41 on the channel 22b.

In the preferred forms of the invention, as exemplified in Figs. 4 and 7, the exposed neck region 45, 45a serves as the locus of hinging action as the beater is deflected circumferentially. In the modification of Fig. 6, the skirt portions 24 of the beater channel slightly into the spindle 13, and may project slightly into the socket 21, as shown, completely concealing the side faces of the rubber. Adequate flexibility in this form is secured by leaving the neck region 45 of the rubber detached from the beater so that opposite sides of the neck region may freely stretch and compress respectively. Covering the side faces of the neck protects them against deterioration.

The backing channel 21 is secured in a socket 21 in the spindle 13 by means of set screws 28 threaded through lugs 29 in the spindle and engaging a side of the channel. In order to prevent the channel collapsing under the pressure of the set screw, ears 31 are punched out of the bottom of the channel, and extend up into the rubber which is molded around them. The ears 31 bridge the space between the side walls of the channel and are registered with the set screws.

The backing channel 21 may be eliminated, and the bare shank portion 32 of the rubber strip secured in the socket 21 and retained by pins 33 extending through holes molded in the rubber, and threaded through the lugs 29 as shown in Fig. 6. Or the spindle may be formed as a hollow shell 13a and provided with longitudinal slots into which the rubber shank 32a

is slid endwise. Beads 34 on the shank 32a, secure the beater against radial movement.

In the operation of the device, the blow of carpet contact causes the channel to recede, mainly in a circumferential direction, with a certain amount of radial depression also. This cushions the blow that is struck, and decreases the injury to the pile of the carpet that would be caused if the beater were rigidly mounted.

We claim as our invention:

1. A suction cleaner beater element for demountable attachment to a rotatable spindle, comprising an elongated strip of rubber, a metal backing channel embracing and secured to one edge region of the strip, parallel to the longitudinal axis thereof, and adapted to be detachably attached to said spindle, and a smooth surfaced, metallic channeled beater bar embracing and secured to the opposite edge region of the strip, parallel to its longitudinal axis, said bar and channel being separated by uncovered areas on both sides of the strip, whereby said bar may freely flex relative to said channel.

2. A beater element for attachment to a rotatable spindle of a vacuum cleaner agitator comprising a strip of resilient material, a metallic backing channel embracing and secured to one edge region of said strip and adapted to be detachably secured in a socket in said spindle, and a lug upstruck from a wall of said channel and bridging the space between the side walls thereof, said lug adapted to withstand the pressure of a set screw opposite the lug bearing against one of said side walls for securing the beater element in said socket.

3. In a suction cleaner, a suction head having a downwardly facing mouth, means for supporting said head for travelling over a rug with said mouth spaced thereabove, suction producing means for lifting a section of the rug into contact with said mouth and for drawing a current of cleaning air over said section, and a rotary agitator in said head, comprising a spindle, and a beater element attached to said spindle, comprising a smooth faced carpet contacting bar of wear resisting material spaced from the periphery of the spindle and parallel to the axis of rotation thereof, and a body of resilient material connecting said bar to the spindle, said body being of such cross sectional area and dimensions, and of such resiliency, as to hold said bar in a substantially uniform path of rotation at all speeds, and yet to allow circumferential deflection of the bar under carpet impact.

4. In a vacuum cleaner, a rotatable spindle, and a beater comprising an elongated strip of soft rubber, one longitudinal edge region of which is attached to said spindle, and a beater channel of smooth surfaced metal embracing and secured to the opposite edge region of the strip, parallel to its longitudinal axis, said channel being adapted to make contact with a carpet being cleaned, and being separated from the spindle by uncovered areas on both sides of the strip whereby the latter may freely flex relative to the spindle.

5. In a vacuum cleaner, a rotatable spindle, and a beater comprising an elongated strip of resilient material, one longitudinal edge region of which is attached to said spindle, and a beater channel of smooth surfaced metal embracing and secured to the opposite edge region of the strip, parallel to its longitudinal axis, said channel being adapted to make contact with a carpet being cleaned, and being separated from the spindle by uncovered areas on both sides of the strip whereby the latter may freely flex relative to the spindle.

- ered areas on both sides of the strip whereby the latter may freely flex relative to the spindle.
6. In a vacuum cleaner, a rotatable spindle, and a beater comprising an elongated strip of soft rubber, one longitudinal edge region of which is attached to said spindle, and a beater channel of smooth surfaced metal embracing and secured to the opposite edge region of the strip, parallel to its longitudinal axis, said channel being adapted to make contact with a carpet being cleaned.
7. In a vacuum cleaner, a rotatable spindle, and a beater comprising an elongated strip of resilient material, one longitudinal edge region of which is attached to said spindle, and a beater channel of smooth surfaced metal embracing and secured to the opposite edge region of the strip, parallel to its longitudinal axis, said channel being adapted to make contact with a carpet being cleaned.
8. In a vacuum cleaner, a rotatable spindle, and a beater comprising an elongated strip of soft rubber, one longitudinal edge region of which is attached to said spindle, and a beater channel of smooth surfaced hard, tough, wear resisting material embracing and secured to the opposite edge region of the strip, parallel to its longitudinal axis, said channel being adapted to make contact with a carpet being cleaned, and being separated from the spindle by uncovered areas on both sides of the strip whereby the latter may freely flex relative to the spindle.
9. In a vacuum cleaner, a rotatable spindle, and a beater comprising an elongated strip of readily flexing, resilient material one longitudinal edge region of which is attached to said spindle, and a beater channel of smooth surfaced hard, tough, wear resisting material embracing and secured to the opposite edge region of the strip, parallel to its longitudinal axis, said channel being adapted to make contact with a carpet being cleaned.
10. In a vacuum cleaner, a rotatable spindle, and a beater comprising an elongated strip of readily compressible resilient material one longitudinal edge region of which is secured to said spindle, and a beater channel of smooth surfaced stainless steel embracing the opposite longitudinal edge region of said strip, its side walls engaging the intermediate region of the strip under pressure and displacing portions of said region inwardly of the normal contour thereof, said channel adapted to make contact with a carpet being cleaned, and said strip allowing said channel to recede circumferentially upon carpet contact so as to cushion said contact.
11. In a vacuum cleaner, a rotatable spindle, and a beater comprising an elongated strip of readily compressible resilient material one longitudinal edge region of which is secured to said spindle, and a beater channel of smooth surfaced stainless steel embracing the opposite longitudinal edge region of said strip, said channel having an aperture, and its side walls engaging the intermediate region of the strip under pressure and displacing portions of said region inwardly of the normal contour thereof and extruding a portion of said strip into said aperture to securely retain the channel against either radial or endwise removal, said channel adapted to contact a carpet being cleaned and said strip allowing the channel to recede circumferentially under carpet contact so as to cushion said contact.
12. In a vacuum cleaner, a rotatable spindle, and a beater comprising an elongated strip of soft rubber, one longitudinal edge region of which is attached to said spindle, and a beater channel of smooth surfaced metal embracing and secured to the opposite edge region of the strip, parallel to its longitudinal axis, said channel being adapted to make contact with a carpet being cleaned.
13. A beater element for use in connection with the rotatable agitator spindle of a vacuum cleaner, comprising an elongated strip of soft rubber having means to attach one longitudinal edge region thereof to the spindle, and a beater channel of smooth surfaced metal embracing and secured to the opposite edge region of the strip, parallel to its longitudinal axis, said channel being adapted to make contact with a carpet being cleaned.
14. In a vacuum cleaner, a motor driven rotary agitator comprising a spindle and a beater secured thereto and projecting radially therefrom, said beater comprising a strip of readily flexing resilient material and a carpet contacting tip of wear resisting material having and capable of maintaining under operating conditions, a smooth, polished contacting face, positioned to engage the carpet when the beater is in carpet contacting position, said tip being substantially coextensive longitudinally with said strip and separated from the spindle by an exposed region of said material forming a flexing neck allowing the beater to recede circumferentially under the impact of carpet contact, and to cushion the blow thereby inflicted.
15. In a vacuum cleaner, a rotatable spindle, and a beater comprising an elongated strip of readily flexing resilient material, one longitudinal edge region of which is attached to said spindle, and a carpet contacting tip of wear resisting material having and capable of maintaining under operating conditions, a smooth polished contacting face, rigidly attached to said strip of resilient material so as to have wiping impact against a carpet, said tip being held in a substantially uniform path of rotation at all speeds, and yet allowed to freely recede circumferentially under carpet impact, solely as a result of the flexibility of said strip of resilient material.
16. In a vacuum cleaner, a rotatable spindle, and a beater comprising an elongated beater channel of smooth surfaced, hard, tough, wear resisting material spaced from the periphery of the spindle, and a body of readily flexing resilient material having an inner region attached to said spindle and having an outer region embraced by and secured to said channel.
17. A beater element for use in connection with the rotatable agitator spindle of a vacuum cleaner, comprising an elongated strip of soft resilient material having means to attach one longitudinal edge region thereof to the spindle, and a beater channel of smooth surfaced wear resisting material embracing and secured to the opposite edge region of the strip, parallel to its longitudinal axis, said channel being adapted to make contact with a carpet being cleaned, and being separated from the spindle by uncovered areas on both sides of the strip whereby the latter may freely flex relative to the spindle.
18. A suction cleaner beater element for demountable attachment to a rotatable spindle comprising an elongated strip of readily flexing resilient material, a backing channel embracing and secured to one edge region of the strip, parallel to the longitudinal axis thereof, and adapted to be detachably attached to said spindle, and a

carpet contacting tip of wear resisting material having and capable of maintaining under operating conditions, a smooth polished contacting face attached to the other edge of said strip of resilient material, said tip being substantially coextensive with said strip longitudinally.

19. A suction cleaner beater element for demountable attachment to a rotatable spindle comprising an elongated strip of readily flexing resilient material, a backing channel embracing

and secured to one edge region of the strip, parallel to the longitudinal axis thereof, and adapted to be detachably attached to said spindle, and a carpet contacting tip of wear resisting material having and capable of maintaining under operating conditions, a smooth polished contacting face attached to the other edge of said strip of resilient material.

FREDERICK RIEBEL, JR.
